UNITED STATES PATENT OFFICE.

WILLIAM KLOCKE, OF NEW YORK, N. Y.

SAFETY DEVICE FOR SLIDE-OPERATING MECHANISM IN PRESSES.

1,407,870.

Specification of Letters Patent. Patented Feb. 28, 1922.

Application filed June 1, 1920. Serial No. 385,509.

To all whom it may concern:

Be it known that I, WILLIAM KLOCKE, a citizen of the United States of America, residing in New York city, in the county of

5 Queens and State of New York, have invented certain new and useful Improvements in Safety Devices for Slide-Operating Mechanism in Presses, of which the following is a specification.

10 This invention relates to drawing presses, and aims to provide improvements therein.

The invention provides a safety connection between the blank-holder or die-carrying slide and the driving part, whereby the 15 specially formed and more difficultly replaceable parts of the blank-holder slide operating mechanism will not be broken or strained when said slide meets with an unusual resistance, such as that arising from an ex- 20 traneous object being left between the blank-holder and die.

The invention further provides a novel combination, hereinafter set forth and defined, for the purpose of safeguarding the 25 blank-holder slide operating mechanism and other parts of the press from injury due to said parts meeting with an extraordinary resistance.

An embodiment of the invention is illustrated in the accompanying drawing, wherein—

Figure 1 is a view in side elevation of so much of a drawing press as is necessary to illustrate the invention;

35 Figure 2 is a view in end elevation of the parts shown in Figure 1, with parts shown in section, and with parts broken away;

The invention is shown as embodied in a well-known type of press, the press shown 40 being disclosed in the Klocke Patent No. 955,173, dated April 19, 1910.

In said drawings, numeral 10 designated a reciprocating slide adapted to carry a blank-holder or die, 11 the bed of the press, adapted to carry the complementary part to that which is carried upon the slide 10, and 12 designates a punch slide, here shown as working through the blank-holder slide; 14 designates the side piece of the press frame.

50 The punch slide is conveniently actuated by a crank shaft 16; the blank-holder slide is also preferably actuated from an eccentric part 18 on said crank shaft, through suitable driving connections. The eccentric part 18 is conveniently a crank pin on a gear 19,

through which motion is imparted to the crank shaft 16.

The blank-holder slide driving connections preferably comprise a slide 20, which slide is conveniently arranged to work on a suitable 60 slideway or gib 22, formed on the outer side of the side piece 14 of the press frame. Any suitable connections between the slide 20 and the blank-holder slide 10 may be provided. A suitable and convenient means 65 comprise an extension 22 on the slide connected, through a crank 24, by a link 25, with a crank shaft 27, which crank shaft is connected with the slide 10 through one or more toggles 28. The rock shafts 27 and 70 associated parts, or their equivalents, are preferably provided on two sides of a mid-plane of the press in order to provide a symmetrical application of the driving force to the slide 10.

75 Resilient means 35 are provided in the driving connections of the blank-holder slide 10, which resilient means are adapted to yield when the blank-holder slide meets with an extraordinary resistance, as, for example, 80 the resistance of an extraneous object left between the blank-holder and die during the coming together of these parts. The yielding of the said resilient part 35 prevents the straining or breaking of the more expensive 85 and less easily procurable parts of the driving connections, for example, the rock shaft 27 and the adjustable connections 38 on the blank-holder slide, or equivalent parts.

The resilient means 35 are conveniently in 90 the form of a bolt 40, having an eye or knuckle head 42, which bolt passes through a socket piece 44 formed upon the slide 20. A coiled spring 46 is arranged between a collar 47 on the bolt 40 and a part of the 95 slide, as, for example, the under side of the socket piece 44. The collar 47 may be so fastened on the bolt by means of nuts 49 on the lower screw threaded end of the said bolt. The tension of the said spring is preferably such that it does not yield under the ordinary pressures of the blank-holder upon the work, but will yield under an extraordinary resistance, such as that caused by an extraneous object between the working 100 parts of the press.

105 Any suitable connections may be provided between the slide 20 and its driving part. Preferably this means comprise a link 55 connected at one end to the eccentric part 110

18, and connected at its other end to the knuckle or eye head 42 on the bolt, by means of a pin 57.

In the case of wide presses and heavy-duty presses, the slide 20 and connections are preferably duplicated at the two sides of the press.

The inventive ideas may receive other embodiments than those herein specifically illustrated and described.

What is claimed is:—

1. A drawing press comprising a frame, a blank-holder or die-carrying slide, a drive-shaft, and driving connections between said slide and shaft, including parts between said slide and shaft, capable of being set to rigidly press said blank-holder slide against a blank, said connections also having a resilient part therein between the drive-shaft and said parts capable of being rigidly set, adapted to yield when said blank-holder slide meets an extraordinary resistance.

2. A drawing press, comprising a frame, a blank-holder or die-carrying slide, a drive-shaft, and driving connections between said slide and shaft including a toggle connected to said frame and to said slide, said connections having a resilient part therein between the shaft and toggles adapted to yield when said blank-holder slide meets with an extraordinary resistance.

3. A drawing press, comprising a frame, a blank-holder or die-carrying slide, a drive-shaft, and driving connections between said slide and shaft, said driving connections comprising a toggle connected to said frame and to said slide, a slide and a resilient part between said driving connection slide and said drive shaft, adapted to yield when said blank-holder slide meets with an extraordinary resistance.

4. A drawing press, comprising a frame, a blank-holder or die-carrying slide, a drive-shaft, and driving connections between said slide and shaft, said driving connections comprising parts between said frame and blank-holder slide capable of being set to rigidly press said blank-holder against a blank, said connections further comprising a slide, a spring-resisted part on said latter slide, an eccentric part on said shaft, and a link connecting said spring resisted part and said eccentric part, said spring resisted part being adapted to yield when said blank-holder slide meets with an extraordinary resistance.

5. A drawing press, comprising a frame, a blank-holder or die-carrying slide, a drive-shaft, and driving connections between said slide and shaft, said driving connections comprising parts between said frame and blank-holder slide capable of being set to rigidly press said blank-holder against a

blank, said connections further comprising a slide, a spring-resisted part on said latter slide, an eccentric part on said shaft, and a link connecting said spring resisted part and said eccentric part, said spring resisted part being adapted to yield when said blank-holder slide meets with an extraordinary resistance, and guiding means for preventing turning of said spring resisted part.

6. A drawing press, comprising a frame, a blank-holder or die-carrying slide, a drive-shaft, and driving connections between said slide and shaft, said driving connections comprising parts between said frame and blank-holder slide capable of being set to rigidly press said blank-holder against a blank, said connections further comprising a slide, an eye-headed bolt, a socket in said latter slide, a spring around said bolt bearing against a part of said latter slide for preventing movement of said bolt in said socket, except when said blank-holder slide meets an extraordinary resistance, an eccentric part on said shaft, and a link connection between said eccentric connection and eye-headed bolt.

7. A drawing press, comprising a frame, a blank-holder or die-carrying slide, a drive-shaft, and driving connections between said slide and shaft, said driving connections comprising parts between said frame and blank-holder slide capable of being set to rigidly press said blank-holder against a blank, said connections further comprising a slide, an eye-headed bolt, a socket in said latter slide, a spring around said bolt bearing against a part of said latter slide for preventing movement of said bolt in said socket, except when said blank-holder slide meets an extraordinary resistance, an eccentric part on said shaft, and a link connection between said eccentric connection and eye-headed bolt, and guiding means for preventing turning of said eye bolt.

8. A drawing press, comprising a frame, a blank-holder or die-carrying slide, a drive-shaft, and driving connections between said slide and shaft, said driving connections comprising parts between said frame and blank-holder slide capable of being set to rigidly press said blank-holder against a blank, said connections further comprising a slide, a spring-resisted part on said latter slide, an eccentric part on said shaft, and a link connecting said spring resisted part and said eccentric part, said spring resisted part being adapted to yield when said blank-holder slide meets with an extraordinary resistance, said latter slide and resilient part being on the outer side of the press-frame.

In witness whereof, I have hereunto signed my name.

WILLIAM KLOCKE.
